(57) CLAIM

The ornamental design for an earphone holder stylus, as shown and described.

DESCRIPTION

FIG. 1 is a perspective view.

FIG. 2 is a front view.

FIG. 3 is a rear view.

FIG. 4 is a side view.

FIG. 5 is a top view; and,

FIG. 6 is a bottom view.

The dotted line in the drawing forms no part of the claimed invention.
